US00D867067S

(12) **United States Design Patent** (10) Patent No.: **US D867,067 S**
(45) Date of Patent: ** *Nov. 19, 2019

(54) **BOTTLE**

(71) Applicant: **RTIC IP, LLC**, Houston, TX (US)

(72) Inventor: **James Matthew Jacobsen**, Houston, TX (US)

(73) Assignee: **RTIC IP, LLC**, Houston, TX (US)

(*) Notice: This patent is subject to a terminal disclaimer.

(**) Term: **15 Years**

(21) Appl. No.: **29/646,937**

(22) Filed: **May 8, 2018**

(51) LOC (12) Cl. **07-01**

(52) U.S. Cl.

USPC **D7/511**

(58) **Field of Classification Search**

(57) **CLAIM**

The ornamental design for a bottle, as shown and described.

DESCRIPTION

FIG. 1 is a perspective view of a bottle showing my new design;

FIG. 2 is a front view thereof;

FIG. 3 is a rear view thereof;

FIG. 4 is a right side view thereof;

FIG. 5 is a left side view of thereof;

FIG. 6 is a top view thereof; and,

FIG. 7 is a bottom view thereof.

The broken lines showing portions of the bottle are for the purposes of illustrating environmental structure only and forms no part of the claimed design.

1 Claim, 6 Drawing Sheets
